UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING MACHINE.

Application filed February 16, 1922. Serial No. 536,884.

To all whom it may concern:

Be it known that I, DAVID S. KENNEDY, a citizen of the United States, residing at Brooklyn, in the county of Kings and State 5 of New York, have invented certain new and useful Improvements in Typographical Casting Machines, of which the following is a specification, reference being had therein to the accompanying drawing.

- 10 This invention relates to typographical casting machines, such as linotype machines of the general organization represented in U. S. Letters Patent to O. Mergenthaler No. 436,532, wherein a melting pot is arranged 15 to deliver molten metal into a slotted mold and up against a composed line of matrices to produce a type bar or slug bearing on its edge type characters corresponding to the intaglio characters of the matrices. In 20 these machines, it is important to provide for the escape of air from the mold, as otherwise the slugs (and particularly their type characters) will be cast in a ragged or porous condition. For this reason, it has been 25 the practise for many years past to provide the mouthpiece of the melting pot with shallow grooves or passages to allow the air to escape during the casting operation. Such an arrangement is fairly satisfactory 30 for the casting of the smaller slugs, but it is altogether inadequate for the casting of the larger slugs, such for instance as those formed with headletter or display characters. The difficulty is that the air, in 35 order to escape, must travel back over or through the molten metal as it is injected into the mold, with the result that a considerable portion is inevitably trapped in the mold, thereby producing air pockets or 40 pores which mar the printing face of the type characters. The old arrangement is also open to other objections, one of which, for example, is the leakage or squirting of the molten metal through the air passages 45 due to the failure of the metal to chill quickly enough to seal these passages.

The present invention is intended to obviate the above and other objections and contemplates a construction whereby the 50 air may be completely expelled from the mold during the casting operation so that the slugs may be cast in as perfect condition as possible. To this end, it is proposed to form the air vents directly in the mold, 55 and preferably in its front or matrix en-

gaging face, so that the molten metal which is injected into the mold from the rear, may drive the contained air before it and expel it through the vents at the front. In this way, the molten metal, instead of hindering the escape of the air, acts positively to expel it from the mold. The molten metal will of course flow into the air passages, but any leakage or squirting of the metal is prevented by its sudden chilling or solidification in the air passages due to the cold condition of the metallic surfaces. The fins cast in the air passages will be carried away on the slug when the latter is ejected from the mold and then removed by the customary 60 trimming knives. The exact form and arrangement of the parts will be fully pointed out in the detailed description to follow:

Referring to the drawings:

Fig. 1 is a front elevation of the improved 75 mold;

Fig. 2 is a vertical section taken on the line 2—2 of Fig. 1;

Fig. 3 is a perspective view of the mold 80 at one end; and

Fig. 4 is a perspective view of a portion 85 of the slug as cast in the mold.

Although equally applicable to a plain or unrecessed mold, the invention has been herein illustrated as applied to a mold of 90 the recessed or headletter variety, which is the form commonly employed for the casting of the larger slugs. As shown, the mold comprises the body portion A, the cap portion A¹, and the intermediate liners A² and 95 A³, these parts being held together in assembled relation by the studs A⁴ projecting up from the body portion A and engaging in notches formed in the opposite ends of the cap portion. The cap portion A¹ is formed 100 in its front face with the longitudinal groove A⁵ and in its under face with the series of transverse grooves A⁶, leaving the blocks or core sections A⁷ projecting into the mold cavity proper. As thus constructed, the mold 105 will cast a slug like that shown in Fig. 4, which comprises the relatively thin body portion B, the overhanging face-portion or shelf B¹ upon which the type characters are formed, and the series of transverse ribs B² 110 projecting from the body portion and giving support to the overhanging shelf. In this connection, it is pointed out that the grooves A⁶ are somewhat deeper than the longitudinal groove A⁵ (Fig. 2), so that the ribs B² 115

(Fig. 4) are slightly raised with respect to the overhanging shelf B^1 and extend across the same to its outer face. These raised ribs are later dressed down by the trimming knife in the customary way.

In accordance with the present invention, the mold is provided with a series of air vents or passages in the form of relatively wide and shallow channels a cut through 10 the front face of the cap portion A^1 and disposed in vertical alignment with the transverse grooves A^6 . During casting, the mold is closed at the rear by the mouthpiece of a melting pot and at the front by a composed 15 line of matrices, in the manner indicated by the dotted lines in Fig. 2. Owing to the presence of the air vents a , however, the mold is left open to the atmosphere at the front, so that when the molten metal is injected into it from the rear, the contained 20 air will be completely expelled therefrom through the vents and thus allow the molten metal entirely to fill up the mold and the matrix cavities. As the mold is thus constructed, 25 it has been found in practice that the slugs may be cast in practically perfect condition and with type characters sharply and clearly defined and free from objectionable pores or other imperfections.

30 During casting, the molten metal necessarily flows into the air vents a , but it almost instantaneously chills and solidifies therein, so that no leakage or squirting can take place. Such instantaneous chilling of 35 the molten metal is due primarily to the location of the vents at the front, where the steel surfaces of the mold keep cold, but the action is considerably aided by reason of their comparatively small dimensions.

40 However, it is equally important that the vents be such that the fins b (Fig. 4) cast therein may be carried away with the slug as the latter is ejected from the mold. It is for this reason that the vents are made 45 relatively wide and narrow, as before mentioned, as thereby the fins are cast with sufficient strength to be drawn out without becoming broken.

The location of the air vents is also important, 50 since the fins b must be completely removed from the slug after casting. In the present instance, and as before noted, the vents are aligned with and lead from the transverse grooves A^6 , so that the fins are 55 actually cast on the raised portions of the ribs B^2 , see Fig. 4. Consequently, during the trimming of the slug, the knife does not act directly upon the fins, which in such circumstances would simply bend over or 60 break, but cuts into the ribs slightly below the points of juncture of the fins therewith, thus allowing the fins to be carried off as a part of the shavings from the ribs.

In the accompanying drawing, the invention 65 has been shown merely in preferred

form and by way of example and as applied to a specific kind of machine, but obviously many changes and alterations may be made therein and in its mode of application without departing from its spirit. Thus, the 70 invention is applicable to any form of typographical casting machine, whether the product of such machine be a slug or a single type or logotype, although, as has been seen, it is particularly applicable to a slug casting machine. Again, the air vents, instead of being formed in the cap portion of the mold, might be cut in the body portion of the mold, or any other suitable portion, so long as they are capable of functioning in 75 the manner set forth. In this connection, it may be stated that, in many instances, the grooves A^5 and A^6 are cut in a special liner which is made separate from the cap portion; and in such case, the air vents might 80 be formed in the liner rather than in the cap portion. These and various other modifications will readily suggest themselves to those skilled in the art and still be comprised within the scope of the invention. It should 85 be understood, therefore, that the invention is not limited to any specific form or embodiment except in so far as such limitations are specified in the claims.

Having thus described my invention what 90 I claim is:

1. In or for a typographical casting machine, a mold open at one side for the injection of molten metal and formed at the opposite side with an air vent. 95
2. In or for a typographical casting machine, a mold formed in its matrix engaging face with an air vent leading from the mold cavity. 100
3. In or for a slug casting machine, a longitudinally slotted mold formed in its matrix engaging face with a series of air vents leading from the mold slot. 105
4. In or for a slug casting machine, a longitudinally slotted mold comprising side and end walls, one of the side walls being formed in its matrix engaging face with a series of air vents leading from the mold slot. 110
5. A linotype mold cap formed in its front face with a series of air vents extending therethrough. 115
6. In or for a slug casting machine, a longitudinally slotted mold comprising side and end walls, one of the side walls being formed in its casting face with a series of transverse grooves and in its matrix engaging face with a series of air vents aligned with and leading from said transverse grooves. 120
7. A linotype mold cap formed in its under face with a series of transverse grooves and in its front face with a series of air vents aligned with and leading from said grooves. 125
8. In or for a slug casting machine, a longitudinally slotted mold comprising side and 130

- end walls, one of the side walls being formed in its matrix engaging face with a longitudinal groove opening into the mold slot and in its casting face with a series of transverse grooves, the said cap being further formed in its front face with a series of air vents aligned with and leading from the transverse grooves.
- 5 9. A linotype mold cap formed in its front face with a longitudinal groove and in its under face with a series of transverse grooves of slightly greater depth than that of the longitudinal groove, said side wall being further formed in its matrix engaging face with a series of air vents aligned with and leading from the transverse grooves.
- 10 10. A linotype mold cap formed in its front face with a longitudinal groove and in its under face with a series of transverse

grooves, the said cap being further formed in its front face with a series of air vents aligned with and leading from the transverse grooves.

10. A mold constructed according to any one of the foregoing claims characterized by the fact that the air vents therein referred to are in the form of relatively wide and shallow channels, for the purpose described.

In testimony whereof, I have affixed my signature hereto.

DAVID S. KENNEDY.
